UNITED STATES PATENT OFFICE

EMIL TYDEN, OF HASTINGS, MICHIGAN

ACCELERATOR FOR DRY PIPE VALVE SPRINKLER SYSTEMS

Application filed October 3, 1928. Serial No. 309,903.

The purpose of this invention is to provide an improved construction in the appurtenance of a dry pipe sprinkler system, commonly called the accelerator, being the element of an apparatus by which the fire extinguishing operation of the apparatus is hastened when decline of pressure in the air pressure region of the system indicates the opening of the sprinkler head and thereby 10 the presence of fire, the specific purpose of the present invention being to prevent the accumulation of water in the chambers of the accelerating apparatus under certain conditions under which such accumulation is liable to occur in the constructions hitherto 15 commonly employed. It consists in the elements and features of construction shown and described, as indicated in the claims.

In the drawings:

20 Figure 1 is a diagrammatic view for showing the relative location of the accelerator appurtenances with respect to the dry pipe valve body and pipe leading to the sprinkler system.

25 Figure 2 is a section on an enlarged scale through the accelerator in the plane of the axis of the duct through which the pressure from the air pressure region of the system has access to the accelerator chambers.

30 Figure 3 is a section at the line 3-3 on Figure 2.

Figure 4 is a section at the line 4-4 on Figure 2.

It is customary in installing a dry pipe 35 sprinkler system, when the same is fully connected to the sprinkler heads, for testing it out as to completeness and safety of all the connections, to admit the water from the water main and allow the system, including the air pressure region thereof, to be filled with 40 water without first introducing air under compression to the air pressure region of the system. In thus testing the system which is equipped with an accelerating apparatus of the exhaust type,—that is, in which the opening of the main valve for admitting the water to the system is hastened by means operating to freely vent the air pressure from the air pressure region, as distinguished 45 from the method consisting in equalizing the

air pressure on both sides of the water main valve by opening a passage from the air pressure region to the interseat chamber below the main valve,—the water obtains access to certain chambers and passages of the accelerator, from which it is excluded in the proper 55 operation of the system.

In the hitherto customary forms of these devices having a chamber provided with a diaphragm partition at whose opposite sides different pressures operate for causing the diaphragm to actuate the means for venting the air pressure region, the construction and arrangement are such that the diaphragm extends in a vertical plane with the compartments at opposite sides of the diaphragm also extending vertically, and by reason of this and other features in these constructions it has been found impracticable to provide 60 means for draining the chamber and passages of the water thus inopportunedly admitted to them, or even to ascertain that such is the condition, without disassembling a considerable part of the structure. And it has been 65 liable to happen that the water thus unknowingly admitted may freeze and burst, or otherwise damage the structure.

The purpose of the present invention is to obviate this defect of the former constructions by providing means preventing the water from being trapped or in any manner retained in any passages or cavities of the accelerator, and to accomplish this purpose without impairing the operation of an accelerator of the type operated by differential pressures resulting at opposite sides of the diaphragm upon the decline of pressure in the air pressure region of the system, causing the diaphragm to actuate the accelerating means.

In the customary constructions of this type 90 means are provided for automatically closing a valve which controls the passage by which pressure from the air pressure region of the system obtains access to the accelerator chambers and through which water would gain like access, when the accelerator has opened this valve for its purpose of causing the main valve to be opened for admitting water to the air pressure region; but in the preliminary 95 testing of the apparatus by flushing the sys- 100

tem this valve is not certain to be operated for closing; partly because the system comprises a pipe through which pressure is communicated for operating the valve-closing means, which pipe has a drain cock which is closed in the normal set-up of the apparatus for its purpose, but which is liable to be opened in the preliminary testing, for the purpose of testing the pipe in question; and 5 this in part creates the possibility of the accelerator chambers being filled with water in the preliminary testing, which is in part the reason for the present invention.

The construction of the apparatus as a 15 whole, and particularly as comprising the means of access of water to the accelerator chambers, and the valve for automatically closing the passage in the normal operation of the construction, should be understood for 20 proper understanding of the present invention which constitutes an improvement upon this construction; and said construction is shown in a general way in the drawings and will now be described.

25 In the drawings, X represents the main body of the casing of the dry pipe valve for which there is provided an accelerating device indicated as to the casing members at A and B, and connection to the air pressure region of the system, and is shown and connected also with the main valve cavity above the water-controlling valve therein by a pipe, D. Certain further connection is shown between the accelerating device and the water 30 pressure region of the system consisting of a pipe, 20, which is provided with a drain cock, 21, which is closed in the normal set-up of the apparatus for its purpose, and through which pipe pressure is communicated for operating 35 the valve above referred to, and hereinafter particularly mentioned, for closing the communication with the accelerator chambers to prevent the access of water thereto, which function,—of closing said valve,—is prevented if the drain cock is opened in the preliminary testing of the apparatus as above mentioned.

Without going further into details with respect to the connections, it may be understood 40 from the drawings that by a pipe, d, leading from the pipe, D, the air pressure of the system obtains access to the accelerator chambers which are connected and provided with devices which operate for opening a valve 45 which controls a free vent to the atmosphere by a port shown at 40 in Figure 1, and indicated in dotted line in Figure 2; and that, in the absence of preventing means, when the system becomes occupied with water instead of air, the water might pass by the pipe, d, into the chambers of the accelerator, where its presence will be injurious and its removal attended with difficulty. On this account there is provided a valve, seen at 60, for closing the 50 passage to the accelerator chambers, through

which passage the air pressure of the system obtains access in the normal operation of the construction, and means for closing said valve when the conditions arise under which water might follow the air into these chambers.

70 The means for closing the valve when the apparatus is operating for fire-extinguishing, so that the air pressure region of the system is occupied by water, are shown in the drawings, and may be briefly described as consisting of a diaphragm, 31, which is exposed to pressure of the water which enters the system, following up the air upon venting the air pressure region for bringing the apparatus into fire extinguishing service, said water 80 pressure reaching the diaphragm, 31, through the pipe, 20, above mentioned, and actuating a plunger, 32, into encounter with the stem, 61, of the valve, 60, forcing and holding said valve to its seat.

85 This construction is fully shown and described in my pending application Serial No. 196,732, filed June 6, 1927, and accomplishes the purpose of excluding the water from the accelerator chambers when the system is operating for fire extinguishing; but, as above explained, when the water is admitted to the system for testing the connections before the system has been connected for charging the air pressure region with air under pressure, the conditions are not certain to be such as to insure the closing of the valve because the operator will frequently neglect to close the drain cock, 21, or may purposely leave it open for testing the drainage; and thus water pressure through the pipe, 20, for closing the valve, 60, will be prevented. And not only in such preliminary testing but in the normal operation of the apparatus when the system is filled with water discharging at the sprinkler heads for fire extinguishment, the valve, 60, may fail to close completely, and the accelerator chambers are thus liable to become 90 filled with water to the impairment of the operation and with liability of damage to the structure by freezing, as mentioned above.

95 For obviating this defect, in the construction shown in the drawings there is provided a sump chamber which has no function in the normal operation of the apparatus for fire extinguishing; and which is normally closed and provided with a drain port at the bottom removable for draining the water which may accumulate therein, as hereinafter explained; and the acceleration chambers are arranged so that they are all above the sump chamber; and said accelerator chambers, and all connecting passages are arranged so that they will be completely drained by gravity, that is, so that there are no trap spaces in which water 100 may be left behind in the gravity drainage of the apparatus into the sump chamber.

105 In the construction shown in the drawings the accelerator unit is made to comprise two 110 cast members, A and B, the member, A, con- 115

taining the sump chamber mentioned, indicated at 100, and the member, B, being mounted above the member, A, containing the accelerator chambers and passages.

5 In the cast member, A, at the side of the sump chamber toward the valve, 60, there is formed an ample duct, 101, for communication of fluid pressure to the upper end of the member, A, and between said member, A, and the member, B, which, as stated, is mounted on the top of the member, A, there is provided by a recess in the under side of the member, B, a chamber which is partitioned into two compartments, 103 and 104, by a flexible diaphragm, 105. To the lower compartment, 103, free access of fluid pressure from the duct, 101, is afforded through ample ports, 106, in a plug fitting, 110, which is screwed through the top web of the member, A, at the 15 opposite side of the horizontally extending upper end portion, 101^a, of the duct, 101. And there is formed in said upper member, B, above the diaphragm-partitioned chamber, a chamber, 111, to which fluid pressure from 20 the duct, 101, has access by way of a duct, 112, in the member, B, which registers at its lower end with a port, 113, through the upper web of the member, B, leading from the duct, 101, of which the duct, 112, thus becomes an 25 extension. Said duct, 112, communicates at its upper end with the chamber, 111, by a passage, 114, in which there is interposed a restriction fitting, 115, whose port of fluid flow, 117, is very small relatively to the cross section 30 of the duct, 101, by which the fluid pressure obtains access, as above described, to the compartment, 103, below the diaphragm, 105.

Fluid pressure communication between the chamber, 111, and the compartment, 104, 40 above the diaphragm is provided through a diaphragm guard, 120, which is interposed in the recess in the under side of the casting member, B, above the diaphragm, said diaphragm guard having a central stem, 121, 45 which is fitted fluid-tight in an aperture formed for that purpose in the web of the casting forming the bottom of the chamber, 111, said stem, 121, being axially chambered to receive and seat a stem, 122, of the dia- 50 phragm. This stem is hexagonal in cross section, its slide bearing in the stem of the diaphragm guard being cylindrical so that there is afforded fluid passages along the diaphragm stem through the stem of the dia- 55 phragm guard from the chamber, 111, to the compartment, 104, above the diaphragm.

For ensuring that the diaphragm, 105, shall be held normally flexed upwardly in its chamber to afford range for its downward move- 60 ment in the enlargement of the compartment, 103, consequent on the lowering of the pressure transmitted through the duct, 101, suffi- 65 cient for the accelerating function for which the construction is provided, there is mounted in the plug fitting, 110, a plunger, 125, 70 stressed upwardly by a spring, 126, against the diaphragm, the spring being initially conditioned for suitably upholding the dia- 75 phragm under the normal condition in the absence of decline of pressure in the air pres- 70 sure region of the system which will cause the operation of the accelerator and adapt it to yield upon the decline in pressure which should cause the operation of the accelerator.

The construction thus far described, it will 75 be understood, is calculated to serve the purpose of differential pressure access to and from the opposite sides of the diaphragm, 105, for the purpose of causing movement of the diaphragm to follow any lowering of the 80 pressure in the air pressure region of the system, for operating means for quick venting of said air pressure and consequent opening of the water main valve. For this purpose the present construction comprises a lever, 85 135, connected for actuation by the dia- phragm stem, as seen at 136, said lever ex- 90 tends liquid-sealed, as seen at 137, out of the chamber, 111, for engaging a latch, 138, on a weighted lever, 139, which is fulcrumed 95 outside the member, C, and conditioned for 100 rocking over its fulcrum by the falling of its weighted end when the latch, 138, is released by the action of the diaphragm under the 105 excess of pressure in the chamber, 111, over 110 the pressure at the under side of the dia- phragm. And said lever has a pin, 140, which in the falling movement of the lever engages the hooked end, 141, of a rod, 142, which ex- 115 tends up along the outside of the member, A, at the opposite side from the duct, 101, said rod having its lower end pivotally attached to a latch, 144, which is pivoted at the lower 120 end of the member, B, said latch, 144, being arranged to engage and uphold the weighted lever, 150 which, when released, drops its weighted end, rocking about its pivot at the 125 opposite end, and operates the connections for venting the pressure regions of the system which are of a familiar character as seen 130 in the drawings and require no further description here.

Returning to the construction in the member, B, which constitutes the present invention, it will be observed that the diaphragm guard, 120, at its upper side, and the member, B, at its under side overhanging the dia- 115 phragm guard, are co-operatively recessed as seen at 150, 151, to form an annular cham- 120 ber or passage; and that the member, B, has a plurality of ports, 152, affording ample fluid flow from the chamber, 111, to said annular passage; and that there is provided in 125 said member, B, a free flow passage, 155, communicating with said annular passage at the lowest point of the latter, said passage, 155, having a free discharge by port, 156, in the bottom web of the member, B, registered with the port, 157, leading into the sump chamber, 100, at the upper side of said chamber. 130

Upon considering this construction it may be understood that when water from the system obtains access past the valve, 60, to the duct, 101, and through the restricted port, 117, of the restriction fitting, 115, into the chamber, 111, it will find its way by gravity through the ports, 152, annular passage formed by the recesses, 150 and 151, the passage, 155, and the port, 157, into the closed sump chamber, 100, which, it will be understood, is normally filled with air at atmospheric pressure, so that said sump chamber constitutes an air trap in which in the normal operation of the apparatus for acceleration 15 the air will be compressed to the full degree of the pressure operating in the chamber, 111.

It will be observed that the stem of the diaphragm guard, 120, protrudes up into the chamber, 111, a substantial distance above the bottom of said chamber through which the ports, 152, lead for gravity flow of the water toward the sump chamber; and upon consideration it will be seen that the gravity outflow from the chamber, 111, will be much more rapid as it is much more free, than the inflow through the port of the restriction fitting, 115, so that the water will never accumulate in the bottom of the chamber, 111, so high as the upper end of the stem of the diaphragm guard; and consequently water will never get access to the passages around the diaphragm stem to the compartment, 104, above the diaphragm. It will be seen, therefore, that there is no chamber or passage in the construction in which water arriving through the duct, 101, can be trapped or retained; and that this result is accomplished without sacrificing or impairing in any respect the primary function of the apparatus for accelerating the fire-extinguishing operation by differential pressures at opposite sides of the diaphragm, 105. It will be understood that the water in the compartment, 103, below the diaphragm obtains free outflow by gravity through the ports through which it enters; and that the duct, 101, into which this outflow below the diaphragm occurs will be emptied by gravity flow in the usual drainage 50 of the system, after its operation for fire extinguishment, preparatory to resetting, and in the drainage after flooding for testing as mentioned.

It will be seen upon reference to the drawings that the members, A and B, are connected together with the ports, 156 and 157, registered with each other for fluid flow, as described, into the sump chamber, and with the port, 113, of the member, A, registered 60 with the lower end of the duct, 112, of the member, B the registered ports being connected by coupling bushings, 163 and 164, respectively, securing said members, A and B, in position with their respective ports thus 65 registered.

It will be understood from the drawings that for protecting the operating connections from the diaphragm, 105, to the drop lever, 150, including the several latch connections, there is provided a cover plate, C, which is applied over said connections and secured to the members, A and B, in any suitable, convenient manner as indicated by bolts, 162.

I claim:

1. In a fire extinguishing apparatus which comprises a sprinkler system having a construction for accelerating the action for admitting water to the sprinkler system characterized by a casing structure containing a chamber and passages affording chamber communication with the fluid pressure region of the system and having a movable element arranged to derive movement from change in the pressure derived from said fluid pressure region, the casing containing also a closed air chamber, the first mentioned chamber having a port of discharge into said closed air chamber at the upper part of the latter; means in the first mentioned passages restricting inflow to the first mentioned chamber relatively to the discharge flow therefrom to the second chamber, said first mentioned chamber and passages thereof to said discharge port being continuously dimensioned for free liquid flow relative to the restriction, and the course of said chamber and passages being continuously downward from the restriction to the discharge port, for preventing accumulation and trapping of liquid in said chamber and passages.

2. In the construction defined in claim 1, the casing structure containing a third chamber located in the lower part of the first mentioned chamber, and having fluid pressure communication with the latter at a substantial distance above the bottom thereof, and having at one side a wall member constituting the movable element mentioned in claim 1 which is movable for expanding and reducing said chamber, said wall member being exteriorly exposed to the pressure of the air pressure region of the system, the passage through which said pressure has access to said movable wall member being large relatively to that by which said pressure has access to the first mentioned chamber, and connections by which said movable wall member controls the acceleration of the fire extinguishing operation of the apparatus.

3. In the construction defined in claim 1, the closed air chamber constituting a sump chamber occupying the lower part of the structure and without communication other than the port mentioned with any other part of the apparatus, said sump chamber being provided with means for draining the water which may accumulate therein.

4. In the construction defined in claim 1, the movable element being a wall member of the first mentioned chamber, said passages

including a duct affording communication from the air pressure region of the system both to the first mentioned chamber and to the outer side of said movable wall member, 5 the latter connection being relatively unrestricted.

5. In the construction defined in claim 1, the casing structure containing a third chamber located in the lower part of the first 10 mentioned chamber and having fluid pressure communication with the latter at a substantial distance above the bottom thereof, and having at its lower side a substantially horizontal wall member constituting the movable 15 member mentioned in claim 1 which is movable for expanding and reducing the chamber capacity, said wall member being exposed at its under side to the pressure of the air pressure region of the system, the passage through which said pressure has access 20 to said movable wall being large relatively to that by which said pressure has access to the first mentioned chamber, an operating stem from said movable wall member extending 25 upwardly into the first mentioned chamber and operating connections from said stem extending airtight out through the wall of said chamber for operating the accelerating means.

30 6. In an accelerator device for a dry pipe fire extinguishing system characterized by a casing structure containing a first and a second chamber having a movable wall in common between them which is movable to expand 35 large one chamber and reduce the other by a differential pressure in said chambers, and passageways affording communication between said chambers respectively and the fluid pressure region of the system, and means 40 in said passages of communication with the first chamber to restrict said communication relatively to the communication of said pressure region with the second chamber; the combination of a closed air chamber contained 45 in said casing structure, means establishing communication between said first chamber and the closed air chamber at the upper part of the latter, the restricting means in the passages to the first chamber being dimensioned for restricting inflow to said 50 chamber relatively to the discharge flow therefrom to the closed air chamber, the first mentioned chamber and the means of communication between the same and the closed air 55 chamber being dimensioned throughout the course of flow from said first chamber to said closed air chamber for liquid flow free relatively to the restricted flow permitted by the restricting means, and said course being continuously downward from said restriction to 60 the closed air chamber, for preventing the trapping of liquid in said first chamber.

7. In the construction defined in claim 6, a sub-chamber which forms the lower part 65 of the first mentioned chamber and of which

one side wall is formed by the movable wall member, said sub-chamber having fluid pressure communication with said first mentioned chamber at a substantial distance above the bottom of the latter, and operating connections by which said movable wall member 70 controls the acceleration of the fire extinguishing operation of the apparatus.

In testimony whereof, I have hereunto set my hand at Chicago, Illinois, this 29th day 75 of September, 1928.

EMIL TYDEN.
